UNITED STATES PATENT OFFICE.

ERNEST E. LAMBERT, OF INDIAN ORCHARD, MASSACHUSETTS.

SMASH PREVENTER.

Application filed May 23, 1925. Serial No. 32,421.

This invention relates to smash preventers for looms, and has for one of its objects the provision of a device of this character which shall be adapted to effect the banging 5 off of the loom whenever the respective shuttle boxes simultaneously contain a shuttle.

A further object of the invention is the provision of a device of the character stated which shall be adapted to effect a banging 10 off of the loom whenever the respective shuttle boxes contain a shuttle and when the lay is back.

A still further object of the invention is the provision of a device of the character 15 stated which can be readily applied to the breast beam and lay of a loom without making any alterations in these or other parts of the loom.

The foregoing and other objects are attained by the construction, combination and arrangement of parts hereinafter fully described and claimed, and illustrated in the accompanying drawings, wherein:

Figure 1 is a view partly in elevation and 25 partly in vertical section illustrating the application of the smash preventer to the breast beam and lay of a loom,

Figure 2 is an elevational view of the lay and those parts of the smash preventer carried thereby,

Figure 3 is a bottom plan view of the parts shown in Figure 2,

Figure 4 is a sectional view taken on the 35 vertical plane indicated by the line 4—4 of Figure 2,

Figure 5 is a top plan view of a fragmentary portion of the breast beam and brake shaft and brake shaft operating means,

Figure 6 is an elevational view of the 40 parts shown in Figure 5,

Figure 7 is a detail sectional view taken on the vertical plane indicated by the line 7—7 of Figure 1, and

Figure 8 is a similar view taken on the 45 vertical plane indicated by the line 8—8 of Figure 1.

Corresponding and like parts are referred to in the following description, and designated in the several views of the accompanying drawings, by similar reference characters.

In the drawings 1 designates the breast beam, 2 the lay and 3 the shuttle boxes of a loom. The rear walls and swells or binders 55 of the shuttle boxes 3 are designated 4 and 5, respectively. As these parts are of well

known construction a further description thereof is deemed unnecessary.

In accordance with my invention, a shaft 6 forming a part of the brake mechanism of 60 the loom, is supported from the breast beam 1 by bearing brackets 7. An arm 8 extending in a rearward direction therefrom, is secured to the shaft 6 by a set screw 9 and has an arcuate rear end portion 8^a. A spring 10 65 exerting a constant upward pull on the arm 8, is secured as at 11 to the breast beam 1 and as at 12 to the arm. A bracket 13 having a rearwardly extending horizontal member 13^a and a vertical member 13^b, is secured 70 to the breast beam 1 for vertical adjustment with respect thereto by screws 14 engaging the breast beam and passing through vertical slots 13^c in the bracket member 13^b. A 75 vertically disposed curved lever 15 is connected at its lower end to the bracket member 13^a for movement about a horizontal axis 16, and is provided intermediate its ends with a horizontally disposed roller 17 contacting with the upper convex edge of the 80 forward curved end portion 8^a of the lever 8. The upper or free end of the lever 15 contacts with a stop 18 carried by a plate 19 which is connected to the bracket member 13^a for adjustment forwardly and rearwardly 85 with respect thereto by means of a screw 20 engaging the bracket member and passing through a slot 21 in the plate.

The parts of the smash preventer heretofore described normally occupy the relative 90 positions in which they are shown in Figure 1, and they are yieldingly held in their normal positions by the spring 10. When the lever 15 is actuated in a downward and rearward direction it will, due to the connection 95 established between it and the shaft 6 by the arm 8 and roller 17, rock the shaft in a direction to apply the brake of the loom with the resulting banging off of the loom. When the lever 15 is released, the spring 10 will 100 return the shaft 6, arm 8 and lever 15 to their normal positions with the consequent releasing of the brake of the loom.

Means for actuating the lever 15 whenever 105 the respective shuttle boxes 3 simultaneously contain a shuttle, is carried by the lay 2 and comprises a lever 22 extending forwardly and rearwardly of the lay and connected to the under side thereof for movement about a horizontal axis 23. The lever 22 occupies a position between a pair of ears 24 110 to which its pivot 23 is secured, and said ears

depend from the horizontal member 25 of a bracket 26. This bracket also has a vertical member 27, and is secured to the lay 2 by bolts 28 with its horizontal and vertical members in contact with the under and rear sides of the lay, respectively. A boss 29 carried by the vertical bracket member 27, is provided with a vertical bore 30 for the reception of a rod 31 and its stem 32. The upper end portion of the bore is reduced to provide a shoulder 33. The rod 31 is thus mounted for vertical movement, the downward movement thereof being limited by nuts 34 threaded on the stem 32 and contacting with the upper end of the boss 29. A spring 35 mounted on the stem 32 between the upper end of the rod 31 and the shoulder 33 normally holds the rod 31 in its lowermost or depressed position against casual movement. The rod 31 is pivotally connected as at 31^a to the rear end of the lever 22, and due thereto this lever is normally held in a substantially horizontal position in which position of the lever a hook 36 secured to the forward end thereof by a set screw 37 is supported out of the path of the free end of the lever 15. A bar 38 extending longitudinally of the lay 2 is pivoted intermediate its ends to the rod 31 by a pin 39. The ends of the bar 38 pass through vertical slots 40 in guides 41 secured to and depending from the bracket member 27. Stub shafts 42 are connected to the front side of the lay 2 by bearing brackets 43. Downwardly and rearwardly extending arms 44 fixed at their front ends to the shafts 42 by set screws 45 have their rear ends disposed below the ends of the bar 38. Upwardly and rearwardly extending arms 46 are secured at their lower ends to the shafts 42 by set screws 47 and are provided with upper angular terminals 48 contacting with the swells or binders 5 of the shuttle boxes 3. Springs 49 mounted on the shafts 42, connected to collars 50 on the shafts, and contacting with the under side of the lay 2, exerts constant downward pressure on the arms 44 and constant rearward pressure on the arms 46 in order to maintain the former out of contact with the bar 38 and the latter in contact with the swells or binders 5 of the shuttle boxes 3.

When the arms 46 are simultaneously moved forwardly, as would occur whenever a shuttle is in each of the boxes 3, the arms 44 are swung upwardly. As the arms 44 are positioned beneath the bar 38, and as the bar is connected to the rear end of the lever 22, this movement of these arms will swing the lever 22 in a direction to depress the front end and carry the hook 36 into the path of the free end of the lever 15, with the result that the hook 36 will contact with and actuate the lever 15 during the backward movement of the lay 2. This actuates the braking mechanism of which the shaft 6 forms a part and results in the banging off of the loom. As the bar 38 is pivoted to the rod 31 the actuation of one set of the arms 44 and 46 in the manner just set forth will not result in the depressing of the front end of the lever 22. Due thereto and since the lever 22 is normally held in inactive position by the spring 35 there is no possibility of the banging off of the loom during the normal travel of the shuttles.

From the foregoing description, taken in connection with the accompanying drawings, it should be apparent that the smash preventer will not bang off the loom during the normal operation thereof, that it will immediately bang off the loom whenever the respective shuttle boxes simultaneously contain a shuttle, and that the loom will be banged off when the lay is back. While I have described the principle of operation of the invention, together with the device which I now consider to be the best embodiment thereof, I desire to have it understood that the device shown is merely illustrative, and that such changes may be made when desired as are within the scope of the invention as claimed.

What is claimed is:

A smash preventer comprising, in combination with the breast beam, the lay, the shuttle boxes and the brake operating shaft of a loom, an arm fixed to the shaft, a bracket fixed to the breast beam adjacent the arm, a lever pivoted to the bracket and contacting with the arm, a lever pivoted to the lay and adapted when in one position to latch with the first named lever to effect the banging off of the loom, a boss secured to the lay, a vertical rod slidable in the boss and pivotally connected to the second lever, a spring exerting a downward tension on the rod, means adapted to limit the movement of the rod under the influence of the spring, a bar pivoted between its ends to the rod, and means carried by the lay and under the control of the shuttle boxes and contacting with the bar, said means being adapted to effect the movement of the second lever into position for engagement with the first when each shuttle box contains a shuttle.

In testimony whereof I affix my signature.

ERNEST E. LAMBERT.
